UNITED STATES PATENT OFFICE.

JOHN C. BAUER, OF CHICAGO, ILLINOIS.

BOILER-FLUE CLEANER.

SPECIFICATION forming part of Letters Patent No. 427,456, dated May 6, 1890.

Application filed August 17, 1889. Serial No. 321,053. (No model.)

To all whom it may concern:

Be it known that I, JOHN C. BAUER, a citizen of the United States, and a resident of Chicago, in the county of Cook and State of Illinois, have invented certain new and useful Improvements in Boiler-Flue Cleaners; and I do hereby declare that the following is a full, clear, and exact description of the invention, which will enable others skilled in the art to 10 which it appertains to make and use the same.

My invention is a new and useful device for cleaning the scales from the outside of the tubes or flues of multitubular boilers.

In the accompanying drawings, illustrating 15 the device, Figure 1 is a perspective view of one of a set of my boiler-flue scrapers. Fig. 2 is a similar view of another of a set. Fig. 3 is a longitudinal vertical sectional view. Fig. 4 represents a cross-section on the line 20 xx in Fig. 3, and Fig. 5 illustrates the method of using my device.

Like letters of reference denote corresponding parts in all the figures.

Referring to the drawings, the letters A A' 25 denote the shanks of a set of my scrapers, which should be provided with suitable handles B B'. From at or near the end of the shank A projects a scraper-blade C, bent inwardly in the form of an arc toward the handle B. The back of this blade is about one-fourth of an inch in thickness and the sides form obtuse angles with the back, making the front face much wider. This front face is gouged out or provided or formed with a 30 central recess a , so that the inner face of each side forms a very acute angle with the corresponding side, and thus two sharp scraping-edges b are formed. The end of the scraper-blade C is sharpened crosswise to form the 35 edge c . The scraper-blade C' projects in like manner from the shank A', but is bent outwardly from the handle B'. It is similar in conformation, except that the end of the blade is sharpened to form a longitudinal edge c' .

40 The method of using my device is shown in Fig. 5. The blade C is intended to be used to scrape the tops of the tubes or flues, the

blade C' to scrape the under side of the flues, and the edges c c' are used to remove the scales and sediment from the ends of the 50 boiler. Each blade C C' has two scraping-edges, as has been shown, so that they will work equally well in either direction. The scraping-edges may be easily sharpened when necessary by simply grinding the sides of the 55 blades. In like manner the edges c c' may be ground from the back.

The shanks in a set of scrapers should vary in length, as it will be found more convenient to use long-shanked scrapers on the lower 60 flues and those with short shanks on the flues in the upper rows.

I am aware that it is not new to construct a boiler-flue cleaner with a shank and a curved blade having a single central cutting-edge, 65 and such is not claimed by me, my invention consisting, essentially, of a shank having a curved cutter-blade with a central recess and two scraping-blades, whereby the effectiveness of the implement is greatly increased. 70 It will also be seen that the scraping-edges in my improved device can be sharpened by simply grinding the outside of the blade, which is a great advantage over the old style of cleaners, before referred to, with a single central cutting-edge requiring both edges of the 75 blade to be inwardly beveled.

Having thus described my invention, I claim and desire to secure by Letters Patent of the 80 United States—

A boiler-flue cleaner consisting of a shank A, having a projecting cutter-blade bent or curved to form an arc and having a central recess a on its scraping-face, two scraping-edges b , and a sharpened point or end, substantially as described.

In testimony that I claim the foregoing as my own I have hereunto affixed my signature in presence of two witnesses.

JOHN C. BAUER.

Witnesses:

JOHN CARMODY,
LOUIS BETHKE.
